UNITED STATES PATENT OFFICE

ALICE C. WESTGATE, OF SAN FERNANDO, CALIFORNIA

GIFT-DISPENSING APPARATUS

Application filed December 13, 1927. Serial No. 239,751.

My invention relates to and has for its purpose the provision of an apparatus of simple and inexpensive construction which is designed for dispensing gifts to children and in 5 a manner to carry out the mythical belief of children that at the end of the rainbow there is a pot of gold which is symbolic of riches and happiness.

I will describe only one form of gift dispensing apparatus embodying my invention, and will then point out the novel features thereof in claims.

In the drawings

Figure 1 is a view showing in front perspective one form of gift dispensing apparatus embodying my invention;

Figure 2 is a rear perspective of the apparatus;

Figure 3 is a central vertical sectional view 20 of the apparatus.

Referring specifically to the drawings, my invention in its present embodiment comprises a substantially flat and hollow base 15 constructed of any suitable material and 25 preferably of rectangular form to provide a receptacle in which relatively large gifts are adapted to be stored for manual distribution to children. This receptacle is provided with a door 16 which is hingedly mounted to 30 control an opening in the upper side of the receptacle through which gifts may be withdrawn from the receptacle.

In advance of the door 16 is an opening 17 in the top of the receptacle, partly surrounded 35 by an upstanding chute 18, the opening and chute being relatively large to permit the depositing of relatively large gifts into the receptacle. In advance of the chute 18 is a U-shaped member 19 which constitutes a platform 40 upon which one may stand in position to receive and deposit the relatively large gifts into the chute 18.

In advance of the member 19 is an upstanding board 20 preferably of semi-circular form and having on its front side printed, painted or otherwise fixed thereto the representation of a rainbow as indicated at 21. The ends of the rainbow terminate contiguous to openings 22 in the board 20, and without 45 in these openings buckets 23 are adapted to

be placed so as to be in gift receiving relation with respect to the lower or exit ends of a pair of curved chutes 24 secured to the rear side of the board 20. The upper ends of the chutes 24 are provided with slots 25 through 55 which relatively small gifts may be deposited in the chutes and under the action of gravity caused to traverse the chutes and to thereby be deposited in the buckets 23. The operator occupying the platform 19 is in position 60 to insert gifts into the chutes 24 as well as to deposit relatively large gifts into the chute 18 as has been described.

From the foregoing structural description it will be clear that the apparatus is made 65 relatively large so that the receptacle 15 is capable of receiving relatively large gifts through the chute 18, while the chutes 24 are adapted to receive small gifts of any character. It will of course be understood that the 70 apparatus can be made of any size desired, but it is the present purpose of my invention to construct the apparatus of sufficient size as to permit the public dispensing or distribution of children's gifts of all sizes and dimensions. 75

In practice, the operator who deposits gifts into the chutes 18 and 24 would be concealed by the board 20 from the view of children in front of the board, so that the gifts deposited 80 in the chutes 24 would appear to be delivered from the ends of the rainbow 21 into the buckets 23, thus conveying to the child the idea that the gifts come from the ends of the rainbow. Those gifts which are too large 85 to be deposited in the chutes 24 are deposited into the chute 18 and hence into the receptacle 15, where they may be withdrawn through the door 16.

Although I have herein shown and described only one form of gift dispensing apparatus embodying my invention, it is to be understood that various changes and modifications may be made without departing from the spirit of the invention, and within the 95 spirit and scope of the appended claims.

I claim:

1. An apparatus of the character described comprising a board in representation of a rainbow having chutes thereon provided with 100

entrance openings through which articles may be deposited into the chutes, and exit openings from which the articles are discharged, the exit openings being disposed adjacent the ends 5 of the rainbow to cause the articles to appear as being discharged from the ends of the rainbow.

2. An apparatus of the character described comprising a board in representation of a rainbow having chutes thereon provided with entrance openings through which articles may be deposited into the chutes, and exit openings from which the articles are discharged, the exit openings being disposed adjacent the 10 ends of the rainbow to cause the articles to appear as being discharged from the ends of the rainbow, and portable receptacles in receiving relation to the exit openings.

3. An apparatus of the character described comprising a receptacle having an entrance opening, a chute above the opening, said receptacle having an exit opening and a door therefor, an upstanding board on the receptacle in advance of the chute, a platform between the board and chute, said board having thereon the representation of a rainbow, openings in the board disposed at the ends of the rainbow representation, chutes on the rear side of the board having exit openings disposed adjacent the openings of said board, and portable receptacles within the openings of the board for receiving articles as discharged from said chutes.
